United States Patent Office

Des. 201,482
Patented June 22, 1965

201,482

FIREPLACE

Paul H. Lever, 2512 Carson, Redwood City, Calif.

Filed Oct. 21, 1963, Ser. No. 77,070

Term of patent 14 years

(Cl. D81—7)

FIG. 1

FIG. 2

FIG. 4

FIG. 3

FIGURE 1 is a perspective view of the new fireplace embodying my design.

FIGURE 2 is a front view, on a reduced scale, of the fireplace with the pipe fragmentarily shown for ease of illustration.

FIGURE 3 is a side view of the fireplace with the pipe fragmentarily shown for ease of illustration.

FIGURE 4 is a top view of the fireplace.

The dominant features of my design reside in the portion shown in full lines.

I claim:

The ornamental design for a fireplace, as shown and described.
